UNITED STATES PATENT OFFICE.

GRANT B. SHIPLEY, OF PITTSBURGH, PENNSYLVANIA.

POLE-TREATING APPARATUS.

Application filed November 17, 1925. Serial No. 69,657.

This invention relates to wood treating apparatus, and particularly to one adapted for treating telegraph and telephone poles, or other similar articles, with liquid preservatives such as creosote or zinc chloride.

It is an object of the invention to provide an apparatus for treating poles which is simple in construction, easy to manipulate, economical to install and operate, one which can be selectively used for uniformly treating the entire body of the pole, or for subjecting merely the butt of the pole to treatment, or impregnating the butt to a greater degree than the remaining portion, as desired, and one in which either the so-called "full cell", or "empty cell" process may be carried out.

It is another object to provide an apparatus of the character referred to in which the several parts cooperate to constitute a self-contained compact apparatus highly efficient in operation and capable of quickly effecting a positive deep penetration within a minimum time, and in which the extents of the butts subjected to treatment, when such portions are alone impregnated or specially treated, may be governed to a nicety.

It is a special object to provide an apparatus of this kind having a pivotally mounted treating cylinder which can be easily and quickly swung to either a horizontal or vertical position, as desired, and without in any way disturbing the normal connections to the treating cylinder for delivering and exhausting the preservative and the compressed air employed in carrying out the methods of bringing about the impregnation.

It is also a special object to provide an apparatus which will be automatically self-sealing against the accidental escape of the preservative from the treating cylinder, and in which the sealing of the cylinder will be enhanced when the same is swung from its horizontal to its vertical condition.

These and other objects of the invention will more fully appear when taken in conjunction with the following description and the appended claims.

In the accompanying drawings, forming part of the application, Fig. 1 is a side elevation of the preferred embodiment of the invention, the treating cylinder being illustrated by full lines in its horizontal position, the position which it assumes when

swung vertically being indicated in dotted lines; and Fig. 2 a plan view of the apparatus shown in Fig. 1, illustrating the connections employed for delivering and exhausting the preservative and compressed air to and from the treating cylinder.

Referring to the drawings 1 designates a pit, at the opposite sides of which are located the bearing standards 2, 2' in which are journaled the laterally extending trunnions 3, 3', respectively, the trunnions being anchored to an elongated treating cylinder 4 in any suitable way. As illustrated, the trunnions form a part of a sleeve or collar 5 which encircles and is directly attached to the cylinder 4.

The trunnions 3, 3' are hollow, being bored to provide passageways therethrough as indicated at 6, 6', both trunnions extending beyond the bearing standards, and terminating in one member of a universal joint. The trunnion 3 at its terminal carries the socket member 7 of a universal ball and socket joint, while the trunnion 3' terminates in like fashion in the socket member 7' of a similar ball and socket joint. The socket members 7, 7' cooperate with the ball members 8, 8', forming the extremities of the conduits 9, 9', respectively, the latter conduit leading from a supply tank 10 for a liquid preservative such as creosote or zinc chloride and is equipped with a suitable cut-off valve 11.

The storage tank 10, as illustrated, is in the form of a so-called weigh tank, equipped with a scale mechanism indicated as a whole at 12, and corresponds generally in structure and mode of operation to the weigh tank shown and described in my previously granted Patent No. 1,081,158, granted December 9, 1913. Preservative is delivered to the weigh tank through pipe 13 equipped with the control valve 14 from a pump 15 adapted to be driven by means of an electric motor 16 through the interposed reducing gear mechanism 17.

A compressed air tank is shown at 18, suitably supported upon the standards 19, 19', which is adapted to be supplied with compressed air by means of an air compressor 20. A pressure of approximately 350 pounds to the square inch is normally maintained in the air compression tank, the air being delivered thereto from the compressor 20, driven by an electric motor 21.

by means of the conduit 22 having interposed therein the control valve 23. Leading from the pipe 22, slightly in advance of valve 23, is a branch pipe 24 equipped 5 with the control valves 25 and 26, the free end of this branch pipe communicating with the atmosphere. The conduit 9 leading to the trunnion 3, previously referred to, is connected with the branch pipe 24 intermediate the valve 25 and the pipe 22, and has 10 interposed therein the control valve 27. Also leading from the branch pipe 24, at a point intermediate the valves 25 and 26, is a pipe 28 for delivering compressed air to 15 the upper extremity of the weigh tank 10, and which has interposed therein the control valve 29.

One end of the treating cylinder 4 is closed, while its opposite end, adjacent the trunnions 3, 3', is equipped with an inlet head 20 provided with the inlet opening 31, adapted to be closed by an inwardly opening door 32 pivotally mounted as at 33, and equipped with the counterbalancing device 25 34. At an intermediate point, and preferably at the upper side thereof, the treating cylinder 4 is provided with a plurality of spaced apart pet cocks, such as indicated at 35, the purpose of which will be subsequently 30 more fully described.

Communicating with the bore 6 of the trunnion 3 is a conduit 36 which communicates with the interior of the treating cylinder at a point adjacent its closed end, the 35 said conduit being carried by and bodily movable with the said cylinder. In a similar fashion, a conduit 37 communicates with the bore of trunnion 3' and enters the interior of the treating cylinder through the bottom 40 of its inlet head, and adjacent its inlet opening, as clearly shown in Fig. 1.

For the purpose of bodily swinging the treating cylinder between a horizontal position, as illustrated by full lines in Fig. 1, 45 and a vertical position as indicated by the dotted lines in said figure, the trunnion 3' has affixed thereto the gear 38 which meshes with a pinion 39 carried at the end of a shaft driven by means of the reversible motor 40 through an interposed gear reduction 50 mechanism shown at 41. In order to properly position the treating cylinder when in a horizontal position and to limit its movement, there is provided a supporting abutment 42 upon which the treating cylinder 55 may rest when in its horizontal position.

The proportions of the several parts interposed between the motor 40 and the gear 38 are such that the treating cylinder will be 60 positively held, without additional auxiliary locking devices, at any point intermediate its horizontal and vertical positions, and in order to enable the cylinder to be easily swung upon its pivotal mounting, the trunnions 3, 3' are preferably located at a point 65

corresponding substantially to that about which the entire treating cylinder with its attached parts would balance.

The inwardly opening door 32 for closing the inlet opening 31 is so mounted that it is 70 rendered self-closing, and it is here particularly noted that upon the swinging of the cylinder from a horizontal to a vertical position, the said door is subjected to a gradually increasing pressure due to the weight of 75 the preservative and the pole being treated, located within the interior of the cylinder, tending to enhance the sealing effect preventing egress or escape of the preservative outwardly through the inlet opening 31. 80

In use, the pole to be treated is inserted through the inlet opening 31 into the interior of the treating cylinder when it occupies a horizontal position. If it be desired to 85 impregnate the entire pole with the preservative, the cylinder is retained in its horizontal position, while admitting the preservative thereto from the weigh tank 10 through the conduit 9', bore 6' of the trunnion 3', and the conduit 37. If a deep penetration is to be effected, the preservative within the treating cylinder may be subjected to any suitable pressure by admitting 90 compressed air to the upper end of the weigh tank, the air being conducted from the air compression tank 18 through the pipe 22, the branch pipe 24, and the pipe 28. 95

After subjecting the entire body of the pole to treatment in this manner, if it is desirable to subject the butt end thereof to an 100 additional treatment to secure a deeper and fuller penetration at this region, it is merely necessary to swing the treating cylinder from a horizontal position to a vertical position, and permit a portion of the preservative 105 to flow back into the weigh tank 10, until the desired level thereof within the treating cylinder is reached. During this step the compressed air previously admitted to the upper portion of the weigh tank, can be discharged to the atmosphere by way of the pipe 28 and branch pipe 24, the valve 25 being closed and the valves 29 and 26 being opened for this purpose. The level of the preservative within the treating cylinder 110 when in its vertical position can be readily determined by opening the several pet cocks 35. After the desired level of the preservative 115 has been determined as just described, the pet cocks 35 being closed, the preservative retained within the cylinder may be subjected to the necessary pressure for securing the desired impregnation by admitting compressed air from the tank 18 to the upper closed end of the treating cylinder. 120 The compressed air finds its way through the pipe 22, the branch pipe 24, the conduit 9, the bore 6 of trunnion 3, and the conduit 36, valve 25 being closed and valves 23 and 27 being open at this time. After the com- 125 130

pletion of the impregnating action of the butt, in this manner, the entire quantity of preservative left in the treating cylinder may be discharged backwardly into the weigh tank by opening the valve 11 and admitting a sufficient quantity of compressed air to the upper closed end of the treating cylinder by means of the conduit 36.

In case the butts of the poles only are to be treated, it is obvious that after placing the pole to be treated within the cylinder, the cylinder will be first moved to its vertical position, a sufficient quantity of the preservative then admitted through the conduit 37 from the weigh tank into the cylinder, its level being determined by means of the pet cocks 35, and the remaining steps being then carried out in a manner similar to that previously described, thus leaving the upper portion of the pole untreated with the preservative.

Due to the ease with which the supplies of preservative and the compressed air, as desired, can be delivered to and exhausted from the treating cylinder, by properly manipulating the several control valves provided, the apparatus readily lends itself to the carrying out of either the "full cell" or "empty cell" process well known to this art.

During the swinging of the treating cylinder between the limits defined by its horizontal and vertical positions, the several conduits 36 and 37 move bodily with the cylinder, but without in any way affecting the delivery or exhaust of the treating fluids, due to the provision of the universal connections located at the extremities of the trunnions 3, 3'.

It is thus seen that the invention provides a very simple, convenient, compact, and efficient apparatus for treating either the entire pole or merely the butts thereof, one by which a positive deep penetration with the preservative may be accomplished in a minimum period of time, one in which the bodily swinging of the treating cylinder does not disturb the normal connections for delivering and exhausting the fluids employed, and one which is automatically self-sealing against the accidental escape of the preservative from the cylinder when it is swung to its vertical position.

I claim:

1. A pole treating apparatus comprising a pivotally supported treating cylinder, said cylinder being provided with an inlet opening at one end thereof, and means for automatically increasing the effective sealing of said inlet opening to prevent escape of the preservative therethrough upon swinging the said cylinder from a horizontal to a vertical position.

2. A pole treating apparatus comprising

a treating cylinder having hollow trunnions 65 extending therefrom, bearings for said trunnions, a conduit joining the first hollow trunnion with the said cylinder adjacent one end of the cylinder, a second conduit joining the remaining hollow trunnion to the other 70 end of the cylinder, and means for delivering and exhausting treating fluids to and from said trunnions.

3. A pole treating apparatus comprising a treating cylinder having hollow trunnions 75 extending laterally therefrom, supporting bearings for the said trunnions, operative connections for the said trunnions to the interior of said cylinder, a conduit leading to a point adjacent each of said trunnions, and 80 a universal joint operatively connecting the extremities of said conduits to the said trunnions.

4. A pole treating apparatus comprising a treating cylinder having trunnions extending laterally therefrom, supporting bearings for said trunnions, one of said trunnions being hollow, means for delivering a liquid preservative to the said cylinder through the said hollow trunnion, and means on said 90 cylinder for indicating the depth of said preservative in the cylinder when the cylinder is swung to a vertical position.

5. A pole treating apparatus comprising a pivotally mounted treating cylinder provided with an inlet opening and having a pair of hollow trunnions extending laterally therefrom, a conduit bodily movable with said cylinder operatively connecting the bore of one of said trunnions to the interior 100 of the cylinder adjacent its inlet openings, a second conduit movable with said cylinder operatively connecting the bore of the remaining trunnion with the opposite end of the cylinder, and a stationary conduit swivelled to each of said trunnions for delivering treating fluid to the bores of the respective trunnions.

6. A pole treating apparatus comprising a treating cylinder, a supply tank for a liquid preservative, a compressed air tank, hollow trunnions fixed to the said cylinder projecting laterally therefrom, supporting bearings for said trunnions, an operative connection from the bore of each of said 110 trunnions to the interior of said cylinder, a conduit operatively connecting the said supply tank to the bore of one of said trunnions, a second conduit operatively joining the said compressed air tank with the bore 120 of the remaining trunnions, said conduits being swivelled to the respective trunnions, and means for bodily swinging the said cylinder between its horizontal and vertical positions.

In testimony whereof, I sign my name.

GRANT B. SHIPLEY.
